UNITED STATES PATENT OFFICE.

ROBERT T. JOHNSTON, OF SCOTCH PLAINS, NEW JERSEY, ASSIGNOR TO R. HOE AND CO., OF NEW YORK, N. Y., A CORPORATION OF NEW YORK.

PLATE FINISHING AND COOLING MACHINE.

1,389,761.

Specification of Letters Patent.

Patented Sept. 6, 1921.

Application filed September 6, 1918. Serial No. 252,888.

To all whom it may concern:

Be it known that I, ROBERT T. JOHNSTON, a citizen of the United States, residing at Scotch Plains, county of Union, and State 5 of New Jersey, have invented certain new and useful Improvements in Plate Finishing and Cooling Machines, fully described and represented in the following specification and the accompanying drawings, forming 10 a part of the same.

This invention relates to certain improvements in machines for cooling and finishing curved stereotype plates.

It is the especial object of the invention 15 to produce a simple, compact machine for finishing and cooling a plate, occupying but small space, and in which two plates may be operated on at the same time and the operating parts of which may be readily accessible to the operator.

A further object of the invention is to produce a machine in which the operating parts are controlled by a fast and loose pulley construction to provide a smooth running 25 machine.

With these and other objects not specifically referred to in view, the invention consists in certain novel arrangements of parts which will now be described in detail in 30 connection with the accompanying drawings, in which—

Figure 1 is a side view, partly in section, of the complete machine;

Fig. 2 is a plan view, partly in section and 35 partly broken away, of the machine shown in Fig. 1;

Fig. 3 is an end view, partly in section, of certain mechanism shown in Fig. 1, and

Fig. 4 is a sectional end view, similar to 40 Fig. 3, showing the parts in other positions, certain parts being omitted.

Referring now to these drawings in detail, the various parts of the mechanism will preferably be supported from a single base 45 1, which may be of any suitable configuration.

Machines constructed in accordance with the invention will include devices for cooling the plate by contact with a cooling fluid and for then finishing the cooled plate. Means will also be provided by the present invention for removing the gate or tail piece formed on the plate during the casting operation. While the specific constructions for effecting these objects may be va-

ried, such constructions will include means whereby the plate is given a rotary movement during the operations of cooling, cutting off the gate and finishing, whereby the mechanisms for effecting these operations 60 may occupy as small a space as possible.

In the particular construction illustrated, there is provided a receiving stand 2 supported through brackets 3 on standards 4 rising from the base 1. Along the receiving 65 stand 2 the plates are fed by the operator to the finishing and cooling mechanism which, in the particular construction illustrated, include a rotary carrier 5 in the form of a hollow cylinder supported in suitable 70 bearing frames 6 secured to the frames 4 of the machine before referred to.

This finishing and cooling cylinder 5 is capacitated to carry two plates around, so that two plates may be operated on, if desired, during the rotation of the cylinder. 75 This cylinder is provided with guide ledges 7 (see Fig. 2) in line with the receiving stand 2, the plate being fed into the cylinder along these guide ledges. In machines 80 embodying the invention in its best form, the plate, as it enters the cylinder, is clamped in position therein. The particular means for effecting this may be somewhat varied, but in the particular construction illustrated 85 there are provided a pair of slides 8, one on each side of the cylinder, provided with locking tongues 9 (see Fig. 2), these slides and tongues having a movement circumferentially of the cylinder, the slides being held in position by being undercut, as indicated at 10, and taking in undercut grooves in the cylinder sides.

In the particular and preferred construction illustrated, each slide 90 has two of these locking tongues. These 95 locking slides are held normally in locked position through springs 11 taking against abutments 12 on the shell and lugs 13 on the slides. These locking slides operate to lift one side of the plate from the guide ledge 7 100 and lock it firmly against the interior of the shell, slots 14 being provided in the guide ledges 7 to permit the operation of the tongues. Various means for operating the locking slides to effect the locking action 105 may be provided. In the particular construction illustrated, there are provided recessed arms 15 in which operate striker pieces 16, the pieces sliding in the arms against springs 17. These arms 15 are oper- 110

ated at the proper time to move the slides against the compression of the spring to place the locking lugs in plate receiving position. In the particular construction shown, 5 the slides are provided with projections 18 which extend into the normal out position of the striker pieces 16. As the shell rotates clockwise in Fig. 3, the projections 18 force the striker pieces inward in the recesses of 10 the arms 15, which strikers, after the projections 18 pass, immediately spring behind them. The striker arms are then operated to compress the springs and operate the slides to permit a plate to be fed into the 15 cylinder. While this may be effected in various ways, in the particular construction illustrated these striker arms are mounted on a rock shaft 20 suitably supported in the frame of the machine. This rock shaft is 20 operated through spring rod connections 21, operable from either end of the machine through foot levers 22, one of which is shown in Fig. 1. By depressing these levers, the operator opens the lock and can insert a 25 plate in the cylinder. When the plate is in the cylinder, the operator releases the foot lever and the plate is locked in position and ready for subsequent operations.

The cylinder may be driven in various 30 ways. As shown the cylinder has fast there- to a driving gear 23 which meshes with a driving pinion 24 on a short shaft 25. This shaft 25 at one end carries a gear 26 which meshes with a pinion 27 on a short shaft 35 28. This shaft 28 is driven through a pair of fast and loose pulleys (see Fig. 1) 29, 30, and a driving pulley 31 on a driving shaft 32 suitably supported in bearings 33 on standards 34 rising from the base 1, before 40 referred to, the pulleys being driven by a suitable belt 35, and the shaft 32 being driven from any suitable source of power as motor 32'.

Where means are employed for removing 45 the gate or tail piece from the plate, these means will include a beveled cutter 36 mounted on a short shaft 37 suitably supported in the frame of the machine, this cutter shaft being driven at a higher speed 50 than that of the driving shaft 32, before referred to, through an ordinary belt and pulley construction 38.

In machines embodying the invention in 55 its best form, means will be provided whereby after the finishing cylinder with a plate therein has made a partial revolution, the cylinder will be automatically stopped to enable the operator to feed into the cylinder an unfinished plate and at the same time re- 60 move therefrom the plate which has been cooled and finished, the operator again starting the machine to complete the revolution of the cylinder. While the particular construction employed for providing for this 65 cylinder movement may be varied within

considerable limits, as illustrated there is provided a controller shaft 39 extending longitudinally of the machine on one side, this controller shaft being provided with operating handles 40, one on each end, so that the shaft may be operated from each end of the machine. From this controller shaft are operated the connections whereby the cylinder is stopped after a partial revolution and by which it is again set in rotation by the operator, these connections in the best 70 constructions including means for preventing the operator from setting the cylinder rotating mechanism in action unless the parts are in correct position, and means for stopping the rotation of the cylinder after the power has been thrown off. The particular mechanism for effecting this may be widely varied. As illustrated, however, the controller shaft carries an arm 41 to which 75 is connected a link 42 having secured at its other end a latch piece 43. This latch piece is normally held through a spring 44, shown in dotted lines in Fig. 3, in position to engage an abutment or stop 45 on the cylinder. The latch is connected at its lower end to one arm 430 of a lever 44' pivoted at 431 in the frame of the machine. The other arm of this lever has connected thereto a rod 432 which passes through an 80 aperture in a bracket arm 433 secured to the frame of the machine, and this rod at its lower end carries adjustable thrust nuts 434. A spring 43' is arranged around the rod and takes between the nuts 434 and the 85 lower face of the bracket arm 433. This construction acts to stop the rotation of the cylinder, the spring 43' taking up the momentum. When it is desired to rotate the 90 cylinder, the operator first moves one of the handles 40 to rock the shaft 39. This movement frees the latch 43 from the abutment 45 and permits the cylinder to be rotated when the power is applied. To apply power 95 the shaft 39 is mounted to slide in its bearings longitudinally of the machine. This shaft has a belt shifting yoke 46 fast thereon and by movement of the shaft the shifting yoke acts to throw the belt from the loose to the fast pulley, thus starting the cylinder 100 through the train of gearing before referred to.

To effect the stopping of the cylinder after 105 partial revolution, the cylinder is provided with a pair of cams 47, one of which is shown (see Fig. 2). This cam, in the rotation of the cylinder, strikes against a cam roll 48 on a cam lever 49 suitably pivoted at 110 50 in the machine frame, the other arm of this lever 51 having a pin 52 taking in a 115 groove 53 of a collar 54 slidable on the controller shaft 39 before referred to, against a spring 55 on the shaft located between the collar and the yoke 46. As the cylinder rotates, one of the cams 47 hits the cam roll 120 125 53 before referred to, against a spring 55 on the shaft located between the collar and the yoke 46. As the cylinder rotates, one of the cams 47 hits the cam roll 130

48 and through pin 52, collar 54 and spring 55 moves the yoke 46 to the left in Fig. 2 and throws the belt 31 from the fast to the loose pulley. The same movement also 5 throws the controller shaft to the left, as yoke 46 is fast thereon and the cylinder is stopped until the controller shaft is again operated, this sequence of movement occurring at each half revolution of the cylinder. 10 In some circumstances if desired the cylinder may be caused to make a complete revolution. To effect this the operator holds the controller shaft pressed to the right in Fig. 2, and the spring 55 takes up the movement of the collar 54 given it by the cam 47. 15 In the best constructions means will be provided whereby the operator can not throw on the power until the latch 43 before referred to has been moved out of engagement with the abutment 45. In the particular construction shown, this is accomplished by means of a locking pin 56 (see Fig. 3), this locking pin being carried on one of the handles 40, before referred to, 20 and as shown in Fig. 1. This pin bears against a projection or lug 57, on a bracket 57' on the machine frame and until the shaft 32 is rotated to allow the pin to clear this lug the shaft cannot be given its endwise 25 power applying movement. The other lug 58, against which the pin snaps after it has cleared the lug 57 acts as a stop and indicates to the operator that the parts are in proper position to put the power on. 30 The specific means for cooling and finishing the plate may vary widely in construction. In the best constructions, the plates are cooled and then finished. In the particular mechanism shown, there is provided 35 a plate 59, shown in edge view in Fig. 2 and in dotted lines in Fig. 3, through which extends a pipe 590 connected with a suitable source of water supply. This plate 59 is connected in any suitable manner as by 40 being secured to a knife block 61 and extends downwardly so as to be close to but to clear the inside surface of a plate in the lower part of the carrier. This plate acts as an abutment or dam to keep the water from 45 running out the left hand end of the cylinder, Fig. 2, and to direct it through the cylinder so that as a plate is rotated by the cylinder it will come into contact with the water and be cooled. After the plate has 50 been cooled, it is finished by a suitable finishing knife 60 carried in a knife block 61, the knife being secured to the block by screws 62. This block 61 may be supported in any suitable manner, as on the uprights 4 55 before referred to. The plate, after it has been cooled and finished, may be delivered in any suitable manner, as on a delivery stand 64 supported from a bracket 65 on the upright 4 before described. 60

While a compact machine, and one in which the parts are readily accessible and easily manipulated by the operator, has been produced by the present invention, it will be understood that the various constructions 70 shown and described may be widely changed as to their specific details without departing from the invention, and it is understood that such changes and variations may be made within the scope of the appended 75 claims.

What is claimed is:

1. In a stereotype plate finishing machine, the combination of a finishing cylinder, means for driving the cylinder, means for 80 disconnecting the driving means after a partial revolution, means for locking the cylinder against rotation, and manually operated means for breaking the lock and throwing the power operating means into operation. 85

2. In a stereotype plate finishing machine, the combination of a finishing cylinder, means for driving the cylinder, means for automatically disconnecting the driving means after a partial revolution, means for 90 locking the cylinder against rotation, and a manually operated controller movable to first break the lock and then throw the power driving means into operation.

3. In a stereotype plate finishing machine, 95 the combination of a finishing cylinder, a fast and a loose pulley and a belt and connections therefrom for driving the cylinder, means for locking the cylinder against rotation, and a manually operable controller 100 for first breaking the lock and then shifting the belt to apply power to the cylinder.

4. In a stereotype plate finishing machine, the combination of a finishing cylinder, means for driving the cylinder, a controller shaft, connections from the controller shaft to the driving means for controlling their operation, a lock for locking the cylinder against rotation, and connections from the controller shaft to the lock for breaking 110 the lock. 105

5. In a stereotype plate finishing machine, the combination of a finishing cylinder, locking abutments thereon, a locking latch with which the abutments coöperate, a controller shaft, connections from the shaft to the latch for making and breaking the lock, driving mechanism for the cylinder, and connections from the controller shaft to the driving mechanism for controlling the latter. 115

6. In a stereotype plate finishing machine, the combination of a finishing cylinder, means for driving the cylinder, means for disconnecting the driving means after the cylinder has been given a partial revolution, 120 and means for rendering the disconnecting means inoperative to permit a full revolution of the cylinder. 125

7. In a stereotype plate finishing machine, the combination of a finishing cylinder, 130

means for driving the cylinder, automatic means for throwing the power driving means out of operation after a partial revolution, and manually operated connections 5 for throwing the power operating means into operation.

8. In a stereotype plate finishing machine, the combination of a finishing cylinder, means for driving the cylinder, a controller 10 shaft, connections from the controller shaft to the driving means for controlling their operation, means for holding the cylinder against rotation, connections between the locking means and the controller shaft, and 15 means whereby the operation of the controller shaft to control the driving means is prevented until the locking means have been released.

9. In a stereotype plate finishing machine, 20 the combination of a finishing cylinder, means for driving the cylinder, a controller shaft having a rotary and a longitudinal movement, locking means for locking the cylinder against rotation, connections between the shaft and the locking means, and 25 means whereby the longitudinal movement

of the shaft is prevented until the cylinder locking means have been released.

10. In a stereotype plate finishing machine, the combination of a finishing cylinder, a fast and a loose pulley and a belt and 30 connections therefrom for driving the cylinder, means for automatically disconnecting the driving means after a partial revolution, means for cooling a plate on the cylinder by contact therewith of a cooling fluid, means for locking the cylinder against rotation, and a manually operated controller 35 movable to first break the lock and then throw the power driving means into operation.

11. In a stereotype plate finishing machine, the combination of a finishing cylinder, means for driving the cylinder, a controller 40 shaft, a yoke fast on the shaft, a 45 collar slidable on the shaft, connections between the collar and cylinder for moving the collar, and a spring between the collar and the yoke.

In testimony whereof, I have hereunto set 50 my hand.

ROBERT T. JOHNSTON.
